UNITED STATES PATENT OFFICE.

OTTO ALWIN SCHMIDT, OF CHELMSFORD, ENGLAND, ASSIGNOR TO THE HOFFMAN MANUFACTURING COMPANY LIMITED, OF CHELMSFORD, ENGLAND.

MACHINE FOR GRINDING BALLS.

1,166,264.

Specification of Letters Patent. Patented Dec. 28, 1915.

Application filed February 16, 1915. Serial No. 3,532.

To all whom it may concern:

Be it known that I, OTTO ALWIN SCHMIDT, a subject of the German Emperor, residing at Chelmsford, Essex, England, have invented a certain new and useful Improvement in Machines for Grinding Balls, of which the following is a specification.

This invention relates to improvements in machines for grinding balls of the class in which a rotating grooved abrading or like disk works in conjunction with a similarly grooved stationary cast iron or other disk, the balls to be ground traveling in the grooves between the two disks and falling if desired into a hopper which is provided at one part of the stationary disk. In machines of this class, or where the abrading disk is grooved, it has been proposed to reduce the pitch of the grooves or the distance between them to such an extent that as the grooves wear the formation of ridges is proportionately reduced, the object being to save trimming of the disk at frequent intervals.

The object of the present invention is to provide improved means for effecting this end without the liability of wedging of the balls which will take place unless means are employed to prevent it when the grooves are so arranged.

Briefly the invention consists in providing means to co-act with a disk or disks having grooves arranged in the way above referred to, whereby some of the grooves only, or some portion of the grooves only, are utilized at one time thereby allowing the balls freedom to roll without wedging while not interfering with their action in preventing the excessive formation of ridges between the grooves owing to the fact that in the course of grinding the whole of the grooves will have been traversed by the balls.

In the accompanying drawings there are illustrated two embodiments of the invention by way of example of ways in which it may be carried into effect.

In such drawings: Figure 1 is a general view of a ball grinding machine of a known type. Fig. 2 is a face view of the stationary disk looking in the direction of the arrow Fig. 1, Fig. 3 is a section of Fig. 2 on line $\alpha-\alpha$, showing also a part of the abrading disk. Fig. 4 is a section of Fig. 2 on line $y-y$ showing also a part of the abrading

disk. Fig. 5 is an enlarged view partly in section of a hopper hereinafter referred to. Fig. 6 is a similar face view of the stationary disk showing another way of carrying out the invention. Fig. 7 is a section of Fig. 6 on line $z-z$, showing also a part of the abrading disk. Fig. 8 is a similar view to Fig. 5, but showing part only of a hopper as used with Fig. 6, and Fig. 9 is a part of a general view of a ball grinding machine in connection with this modification.

Referring first to the form shown in Figs. 1 to 5, the complete machine comprises usually a disk 1 of abrasive material driven from a spur wheel 2 by a pulley 3 through a suitable pinion 4, and a stationary disk 5 usually of cast iron which carries the hopper 6 and is kept pressed against the abrasive disk by means indicated by the hand wheel 7 screwed spindle 8 and spring 9. The abrasive disk 1 has a number of grooves 10 on its face placed as close together as possible and each half of the stationary disk 5 has a number of grooves 11 and 12 out of line with each other on the lower and upper half respectively each of such grooves being 75 thus adapted to co-act with alternate grooves only, in the abrasive disk. The grooves 11 and 12 are connected at one point of the disk 5 by a shunting device 13 inserted in its face, while at a point preferably 80 diametrically opposite, if the fixed disk is arranged with grooves 11, 12 in halves, there may be, and is preferably inserted a mixing hopper 6 of some known type for the purpose hereinafter described, or a second shunting device must be used. The shunting device 13 is formed of three blocks 14, 15, 16, having a number of passages 17 connecting the grooves 11, 12, and therefore 85 inclined as shown for such purpose. The shunting device is formed as described in three parts for convenience only in manufacture and such parts are kept together by a back plate 18, and screws 19 passing into same through the plate, while screws 20 are 90 employed for holding the plate to the back of the disk 5. The object of the passages 17 being to pass the balls from a groove 11 to a groove 12, the shunting device must be arranged to pick out the balls as they travel 95 around in the combined grooves 11, 10, and discharge them to the combined grooves 12, 10. For this purpose the passages 17 pro-

ject, at their entering and leaving ends into the space between the two disks by forming the passage in blocks 14 and 16 with a tongue 22 and 21 respectively. Further, 5 owing to the inclination of the passages 17 necessary to connect the grooves 11 and 12 the balls must be brought away from the face of the disk 5 otherwise they would damage the grooves 10 of disk 1, and this 10 is effected by causing the passages 17 to retreat from the face of the disk 5 as shown in Fig. 4 and to approach it again only when the necessary inclination in the direction of travel has been attained, such 15 inclination being principally effected in the central block of the shunting device 13 as shown in Fig. 2. By this arrangement the balls which have been traveling around in the grooves 10, 11, are changed into the 20 other sets 10, 12, the grooves 10 in the abrading disk (of which there are double the number of the grooves 11, 12) being from time to time all occupied by the balls though all such grooves 10 are not occupied at the 25 same time. What actually takes place is that with the twelve grooves 10 shown in the disk 1, one half of the grooves say, one, three, five, seven, nine and eleven, will be full of balls and actively grinding during 30 their travel over one half of the disk 5, while one half of the grooves, say, two, four, six, eight, ten, and twelve will be similarly full and grinding during their travel over the other half of the disk 5. Thus, as each 35 of the complete grooves 10 in the revolving disk 1 is occupied from time to time by balls there is a partial overlapping of the grooves which such balls form in the abrasive disk, and hence ridges are prevented from forming 40 to any extent, or are worn down as formed. In other words the twelve grooves 10, in the revolving disk 1, co-act with the grooves in the stationary disk 5 in such a way as to form complete passages, so that 45 when balls are inserted between them only alternate grooves in the revolving disk (together with the co-acting grooves in the stationary disk) are full of balls, those formed by the grooves 10, 12, being intermediate 50 with those formed by the grooves 10, 11. The hopper 6 in this instance fulfills its usual functions of mixing the balls, of enabling the balls to be filled into the grooves, for sampling, and other purposes and differs only from that usually employed by 55 reason of the side plates 23, 23, which are inclined and replace the usual side walls of the hopper generally concentric with the grooves. It also performs the function of 60 a shunting device as while mixing the balls it also transfers them from the upper co-acting grooves 10, 12, to the lower co-acting grooves 10, 11. The usual deflecting edge plate 24 which assists the balls to leave the 65 grooves and discharge into the upper race

25 of the hopper is also employed. 26 are bolts for securing such edge plate 24 and 27 is the lower race of the hopper into which the upper discharges, and which in turn feeds the balls back into the grooves between division plates 28 which form between them spaces corresponding to the grooves in the disk 5, the side plates 23 directing the balls to such grooves. The part 25 of the hopper is secured to the disk 5 by bolts 70 one of which is shown at 40 and the part 27 is similarly secured by bolts which are not shown. These bolts pass through brackets 41, 42, which carry the hopper portions 25, 27, respectively. 75

In the arrangement shown in Figs. 6 to 9, the abrading disk 1^a is shown as having the same number of grooves 10^a as the disk 1, which grooves are either formed or allowed to form therein, but the stationary disk 5^a has also a corresponding number of grooves 11^a. To operate a machine under these conditions the balls are permitted to pass only into alternate grooves in both disks for a period and are then permitted to pass only 80 into the intermediate grooves for another period with the result that an even wearing of the abrading disk or reduction of ridges, is obtained, by the partial overlapping of the grooves which such balls may form in 85 the abrading disk and the full surface is utilized. In this case the change is effected by means of the hopper 6^a which is provided with division plates 28^a dividing the hopper into one half the number of spaces 30 as 90 there are grooves in each disk. The hopper is in addition movable radially or laterally the pitch of the grooves, for which purpose it is slidable by means of dovetails and grooves 31 in the back of the stationary disk 5^a, this movement being effected by means of 95 a cam 32 on the end of the handle 33 pivoted on a spindle 34 fixed in the disk 5^a, such cam working in a slot 35 of the bracket herein-after referred to. By shifting this cam 100 either to the right or left the correct travel of the hopper is effected. The hopper in this case is in one piece, the parts 25^a, 27^a, being carried in a single bracket 44, Figs. 8 and 9 so that the whole can slide with a movement of the handle 33. The hopper may 105 have the usual deflecting edge plate 24^a for the balls. When the machine is started the balls will run say around the grooves, one, three, five, seven, nine, eleven, and form a 110 corresponding set of grooves 10^a in the co-acting abrading disk 1^a or will travel in a set previously formed. After a time and preferably when the hopper has been 115 emptied and withdrawn rearwardly the 120 hopper is shifted radially exactly the pitch of the grooves so that when say a new batch of balls are now fed from the hopper they run around in grooves, two, four, six, eight, ten, twelve and form corresponding grooves 125 130

10^a in the abrasive disk, or travel in a set previously formed. Such grooves it will be seen fall between those formed or traversed by the balls previously. After a time the 5 hopper is shifted back again into its original position for a new batch of balls. The division plates in the hopper could of course be moved in place of the entire hopper. By this means not only do the ridges between 10 the rows of balls in the abrasive member wear away and keep the depth of the grooves uniform, but the same happens in the case iron or like disk which likewise does not have to be turned to reduce the ridges between 15 the grooves.

The constructions above described may be considerably modified in their details without departing from the spirit of the invention.

20 What I claim is:—

1. In a machine for grinding balls, and in combination, a grinding body having a number of grooves formed therein lying so closely together that if they were all filled 25 with balls, those in adjacent grooves would contact with each other and means co-acting therewith for causing the balls to travel in some of the grooves only, at one time to prevent excessive ridges being formed in the 30 grinding body and to utilize the full surface of same.

2. In a machine for grinding balls, and in combination, a grinding body having a number of grooves formed therein lying so closely together that if they were all filled 35 with balls, those in adjacent grooves would contact with each other, and means co-acting therewith for causing the balls to travel in some portion of the grooves only, at one time to prevent excessive ridges being formed 40 in the grinding body and to utilize the full surface of same.

3. In a machine for grinding balls and in combination, a grinding body having a number of grooves formed therein lying so closely together that if they were all filled 45 with balls, those in adjacent grooves would contact with each other, and means co-acting therewith for causing the balls to travel in alternate grooves in the first body, and for utilizing in turn all of same so that excessive ridges are prevented from forming during grinding, and the full surface of the 50 grinding body is utilized.

55 4. In a machine for grinding balls, and in combination, two co-acting bodies adapted to grind the balls between them, means adapted to form such a number of grooves in one of same by the action of the balls, 60 that if they were all occupied by balls those in adjacent grooves would contact with each other such means consisting of the other body which has a lesser number of grooves which are out of line with each other, and a 65 shunt device for connecting such last named

grooves and carrying the balls free of any ridges which may be forming in the first named body.

5. In a machine for grinding balls, and in combination, a grinding body having two sets of grooves each occupying a portion of its surface only and being out of line with each other, a shunt device containing a series of grooves connecting such non-linable grooves, and a second rotatable disk in which is adapted to be formed a series of complete grooves equal in number to the two sets of grooves in the first disk, and arranged so close together that if all were occupied by balls those in adjacent grooves would contact with each other.

6. In a machine for grinding balls, and in combination, two opposed bodies, one having a series of grooves on its face in the relation of two to one of the other, the grooves of the latter extending a part of the way over its face only and being out of line with each other, means at two points of the latter body for enabling the balls to pass from one non-linable groove to the other, the grooves in the first body being arranged so close together that if all were occupied by balls those in adjacent grooves would contact with each other.

7. In a machine for grinding balls, and in combination, two opposed disks, one having a series of grooves on its face in the relation of two to one of the other and arranged so close together that if all were occupied by balls those in adjacent grooves would contact with each other, the grooves in the latter extending a part of the way only around the surface of the disk the grooves in each part being out of line with those of the other part, means at one point of the latter disk for shunting the balls to enable them to pass around the non-linable grooves, a mixing hopper at another point of the latter disk, and directing means combined with same, all co-acting with the shunting means to enable the balls to pass around the non-linable grooves of the disk.

8. In a machine for grinding balls, and in combination a grinding and a holding disk, the latter having two sets of grooves each occupying a portion of the surface only and being out of line with each other, a shunt device in the holding disk containing a series of grooves inclined to connect such non-linable grooves and further retreating from the face of the first disk, and a second shunt device in such holding disk for further connecting such non-linable grooves, the first named disk having its grooves arranged so close together that if all were occupied by balls those in adjacent grooves would contact with each other.

9. In a machine for grinding balls and in combination, two co-acting bodies adapted to grind the balls between them, a part car-

ried by one body, adapted with such body to form such a number of grooves in the other body by the action of the balls, that if they were all occupied by balls those in adjacent grooves would contact with each other, such part directing the balls into certain positions, and traversing them in, certain grooves in each of the bodies and thereafter in other grooves, so that contact of the balls with each other and the formation of excessive ridges is prevented.

10. In a machine for grinding balls and in combination, two co-acting bodies adapted to grind the balls between them, means

adapted to form such a number of grooves in one of same by the action of the balls that if they were all occupied by balls those in adjacent grooves would contact with each other, and a feeding device for the balls having means for selecting the formed 15 grooves in which the balls are to travel.

In testimony whereof I have set my hand in the presence of two subscribing witnesses.

OTTO ALWIN SCHMIDT.
